DRESS CONSTRUCTION

Harry D. Lytle, New York, N. Y.

Application January 30, 1941, Serial No. 376,693

1 Claim. (Cl. 2-74)

This invention relates to apparel, and has reference more particularly to a dress of the ready made type which is manufactured in quantity production for women and young ladies.

At the present time a merchant must buy a large number of dresses of different sizes and patterns in order to be adequately stocked, as a customer may like a certain pattern or style of dress and sales are often lost due to the fact that while the customer may like a certain dress, the merchant does not have a dress of this particular type which will properly fit the customer. Sales are also lost due to the fact that while a dress may be altered by taking in seams, there is not enough material in the seam to allow the dress to be let out when necessary. At present it is customary to provide greater fullness where needed by inserting gussets, but this is not satisfactory as the gussets are unsightly and many customers refuse to accept a dress so altered. In addition, it is often difficult to obtain the extra material necessary for a gusset in a fabric which will be a perfect match to the dress and even if the needed material can be obtained from the manufacturer of the dress, sending for it involves delay which is very annoying and often results in loss of a sale due to the fact that the customer desires quick delivery.

It has also been found that when certain customers try on a dress, the waistband does not fit properly but has a tendency to ride upwardly at certain points and spoil the appearance of the dress. One reason for this is that a woman with a large bust or abdomen or a fat back takes up the material and causes the waistband to rise on her figure. Depending on the figure, this rise may occur equally all around the waistband, or may be greater at the center of the back and front and less at the sides of the dress. In addition, some women are long-waisted. Women's dresses are made in two ranges of size principally affecting the length of dress. The half size range is for the shorter women under 5' 5" in height. The regular sizes, so called, are for the taller women of 5' 5" or over. Even the regular sizes, however, are intended for a woman of normal stature, and an exceptionally tall woman, even though not stout enough to cause the waistband to rise above the level planned for in the construction of the dress, may actually have a normal waistline lower than that provided in the garment. For this last type of figure, the extra material provided in the hemline of most dresses is insufficient to give the dress the required length and even if it were sufficient, would not permit

the waistline of the dress to be adjusted so that it maintained its proper relation to the waistline of the woman.

Therefore, it is one object of the invention to provide a dress so constructed, that the seams may be let out where needed as well as being taken in and thus permit a dress which does not fit properly in certain places to be easily altered. This is particularly advantageous as many merchants cannot buy a complete range of sizes in every color in which a dress may be made, or, if they have purchased a complete range, may sell certain of these sizes which might leave them without the size a particular customer required in any particular style or color she might select. In the ordinary dress it is possible for the merchant only to fit a customer who might take a smaller size than the dress he has in stock. The features provided in this invention make it possible for him also to fit a customer who would ordinarily require a dress one or two sizes larger than the dress in stock, by making it possible for him to alter a dress by letting it out where necessary.

This invention is illustrated in the accompanying drawings wherein—

Figure 1 is a perspective view of a dress having the improved construction, the dress being turned inside out;

Figure 2 is a fragmentary perspective view showing the dress turned inside out and illustrating the manner in which a sleeve is applied and also showing the connection between the blouse and skirt and the manner in which a side opening is formed in the dress;

Figure 3 is a fragmentary perspective view of the sleeve;

Figure 4 is a perspective view showing the manner in which the skirt is secured in overlapping relation to the blouse along the waistband of the dress;

Figure 5 is a perspective view showing the lower portion of the skirt turned inside out and illustrating the manner in which the hem of the skirt is formed, the dotted lines showing the manner in which the skirt is lengthened; and

Figure 6 is a view similar to Figure 5 upon an enlarged scale.

The dress may be formed of any material desired and of any preferred design. In the illustration, the dress includes a blouse 1 and a skirt 2, the blouse being provided with sleeves 3 which may be of any length desired. It will be understood that the sleeves may be omitted, if so desired, and that the side opening 4 which is closed

by a slide fastener 5 of the well known construction may be located at any point desired. There has also been shown a rear opening 6 which may be located at the front of the garment or across the shoulder.

The blouse and the skirt are formed of a suitable number of sections or gores which are seamed to each other, except at the sides of the dress or at other points where it is necessary to make alterations for proper fit. At these points the sections or gores are connected by seams 7 having very wide flaps 8 which are sewed to each other by a line of ordinary stitching 9.

An alteration card 10 has been shown applied to each of the wide seams 7. This card, if used, is applied when the garment is made and remains in place until the garment is sold and the necessary alterations are made. These cards are of the type shown in my prior patent, No. 2,090,610, issued August 17, 1937, and are marked to indicate alterations necessary to transform a dress into a dress of the various sizes in the group in which the manufactured dress is included. Provision of the cards makes it very easy for a fitter to ascertain and make note of the extent to which a dress must be let out or taken in for proper fit. The cards may be omitted if so desired and alterations made as deemed necessary by the fitter.

Referring to Figures 2 and 3 it will be seen that the seams for the sleeves are identical in construction to the seams of the blouse and the skirt so that the sleeves may be let out, if too tight as well as taken in, if too loose.

The waistband 11 of the garment is originally made to extend in a straight line and to fall in its proper place in relation to the actual waistline of the eventual wearer. It can be readily understood that if by reason of the purchaser having an excess of flesh either in her bust, abdomen or back, the waistband may be drawn upwardly at the front or back; or by reason of the eventual wearer having a lower waistline, than the figure for which the dress was originally planned, the waistband of the dress will not occupy its proper position in relation to the actual waistline of the customer when the dress is worn, and this will spoil the appearance of the dress. In order to overcome this, the skirt is applied in overlapping relation to the lower edge of the blouse, as shown in Figures 2 and 4. This provides 1½" of extra length in the blouse which may be utilized in full, or in part, as required by the figure of the individual customer. Referring to Figures 2 and 4, it will be seen that the marginal edges of the blouse and the skirt are provided with edging strips or bindings 12 and 13 formed of silk or other suitable fabric.

The upper edge portion of the skirt extends upwardly in overlapping relation to the lower edge portion of the blouse quite a distance and its upper edge is secured to the blouse by a line of stitching 14. If it is found that the waistline is drawn upwardly at the front or back of the dress when the dress is tried on, it is merely necessary

for the fitter to rip out the stitching 14 and after properly adjusting the skirt, pin or baste the skirt to the blouse and later on permanently sew the adjusted skirt to the blouse. The fact that the edges of the blouse and the skirt are bound with the tapes 12 and 13 provides a neat finish for these edges and also causes the upper edge portion of the skirt to be reinforced and held smoothly in place when it is permanently sewed to the blouse. In addition the tapes also hold the edges of the two pieces of the garment straight when they have been separated from one another thus simplifying the job of altering, and as a permanent part of the dress, the tape prevents the waistline from stretching.

This improved dress has its lower edge faced or bound with a strip 15 of silk or other suitable fabric which projects from the edge of the skirt material as shown in Figures 5 and 6. The skirt as initially cut is of such length that it will be of the proper length for the largest dress in its size group and the lower portion of the skirt is turned upwardly and the binding or facing strip 15 hand felled to form a relatively wide hem 16. The wide seam outlets are continued in that portion of the dress which is turned up to make the hem so that if it is necessary to let down the hem, and also to let out the dress, sufficient material is provided so to do.

It will thus be seen that one dress of the improved construction can be made to fit a greater number of customers than a dress of ordinary construction; can be made to fit figures which cannot be properly fitted by altering the ordinary dress; will give most women a better fit than is possible with the ordinary dress; and can be altered at lower cost than the ordinary dress. It will also be seen that when a dress is altered to correctly fit the customer, it will be neat and of attractive appearance.

While I have shown the preferred embodiment of my invention, it is to be understood that various changes may be made without departing from the spirit of the invention and the scope of the appended claim.

Having thus described the invention, what is claimed is:

In a garment, a blouse and a skirt, the back of said skirt being initially free from the blouse and having its upper end portion overlapping the outer face of the lower end of the back of the blouse an appreciable distance permitting shifting of the skirt upwardly and downwardly to adjusted positions without moving out of overlapping relation to the blouse, a binding secured along the lower edge of the back of said blouse in straddling relation thereto, a facing strip secured along the inner face of the upper edge portion of the back of said skirt, and stitches along the upper edge of the back of said skirt adapted to be ripped out and permit vertical adjustment of the back of the skirt relative to the overlapped portion of the blouse.

HARRY D. LYTTLE.
